[57] ABSTRACT

A spark plug cleaner includes a cylindrical container with cleaning fluid and has internally threaded apertured ends. A plug mounting a file is threadedly engaged in one end and a second plug mounting a brush is threadedly engaged in the other end. The file and the brush are used to clean the plug. The apertures in the ends of the container are adapted to receive a threaded end portion of a spark plug to be cleaned. The file and brush are axially offset with respect to each other to permit them to nest and mutually clean each other as they are replaced in the container.

SPARK PLUG CLEANER

BACKGROUND OF THE INVENTION

This invention relates to devices for the cleaning and maintenance of spark plugs and, more particularly, to a spark plug cleaner suitable for the cleaning and maintenance of spark plugs for recreation vehicles such as motorcycles, snowmobiles, boats, dunecycles and the like.

The use of motorcycles, snowmobiles and other similar recreation vehicles is rapidly increasing and the nature of these vehicles and their use is such that the user is often far removed from service facilities in the event of a mechanical breakdown. Furthermore, these vehicles are for the most part powered by two cycle gasoline engines in which about 90 percent of all engine failures are due to spark plug fouling. The problem is particularly aggravated when it is considered that the engines for these types of vehicles generally run at higher temperatures than automobile engines, making spark plug life extremely erratic.

There have been a number of spark plug cleaning devices disclosed in the prior art, but none has been completely satisfactory. Accordingly, it is the primary object of the present invention to provide a spark plug cleaning device that will be able to clean and maintain on an emergency basis the spark plugs used in motorcycles, snowmobiles and similar recreation type vehicles.

It is a further object of the present invention to provide such a cleaning device in a self contained unit wherein the elements themselves are cleaned and maintained as they are assembled together following a particular spark plug cleaning use.

SUMMARY OF THE INVENTION

My spark plug cleaning device comprises a cylindrical container for containing a cleaning fluid and has end closure means for each end of such container. A first internally threaded aperture is axially disposed in one of the end closure means. A first externally threaded plug means is adapted to be removably received in such first internally threaded aperture and generally axially extending file means are mounted in such first externally threaded plug means for internal disposition within said container.

A second internally threaded aperture is axially disposed in the other end closure means and a second externally threaded plug means is adapted to be removably received in such second internally threaded aperture. Generally axially extending brush means are mounted in such second externally threaded plug means for internal disposition within said container.

The file means and the brush means are offset axially with respect to each other to permit the same to nest together and mutually clean each other as they are replaced in the container.

Each of the internally threaded apertures in the end closure means of the container is adapted to receive a threaded end portion of a spark plug to be cleaned. Optionally, the diameter of each of such internally threaded apertures is adapted to receive a spark plug threaded end portion for a spark plug of a different diameter. When the container with a thus threadedly attached spark plug is shaken, the cleaning fluid cleans the threaded end of such plug.

DESCRIPTION OF THE DRAWINGS

FIG. 1 is a perspective view of the spark plug cleaning device of my invention.

FIG. 2 is a longitudinal cross-sectional view of the device of FIG. 1.

FIG. 3 illustrates a use of the file means in cleaning a spark plug.

FIG. 4 illustrates another use of the file means in cleaning a spark plug.

FIG. 5 illustrates a use of the brush means in cleaning a spark plug.

FIG. 6 illustrates the device with a spark plug threadedly engaged in an end portion thereof.

DESCRIPTION OF PREFERRED EMBODIMENT

Referring to the drawings, my spark plug cleaning device 10 includes a cylindrical container 11, which may be injection molded or vacuum drawn from plastic in two halves 12 which are welded together in a centrally located, circumferentially extending seam 13. Each of the molded halves 12 is provided with an end closure 14 which is itself provided with an internally threaded (female) aperture 15, one such end closure 14 preferably being provided with an 18 mm. internal thread diameter and the other a 14 mm. internal thread diameter for the reception of spark plugs of those sizes. Optionally, the container can be made from 1½ inch diameter plastic tubing to which end closures as above described are welded.

A first molded or vacuum drawn plastic cover 16 having a knurled periphery 17 and an externally threaded, axially disposed (male) plug 18 of preferably, 18 mm. thread diameter is provided for the corresponding end closure 20 of the container 11 (end A). A 0.025 inch thick generally axially extending metal file 21 is eccentrically mounted in the plug 18 such that when the latter is threadedly engaged with the corresponding aperture 22 in end A, the file 21 is disposed internally within the container 11, although axially offset with respect to the axis 23 thereof.

A second molded or vacuum drawn plastic cover 24 having a knurled periphery 25 and an axially disposed externally threaded (male plug 26 of preferably, 14 mm. thread diameter is provided for threaded engagement with the internally threaded aperture 27 in the other end closure 28 (end B) of the container 11. An axially extending horsehair brush 30 is centrally mounted in the plug 26 such that when the same is threadedly engaged with its corresponding aperture 27 in end B, the brush 30 is internally disposed within the container 11, being axially aligned with the axis 23 thereof.

The plugs 18 and 26 are each provided with sufficient threads to maintain a liquid-tight seal for the container 11, thus securely to retain cleaning fluid therewithin and prevent inadvertent loss therefrom.

It is noted that the 18 mm. thread diameter of aperture 22 in end A and the 14 mm. thread diameter of aperture 27 in end B fit the two most common spark plug thread sizes currently in use. It is further noted that the 0.025 inch thick file 21 can be used as a guide for setting electrode clearances inasmuch as the same are generally of that dimension. If desired, however, the shank of the file may be of a stepped construction to correspond with differing spark plug electrode gaps.

In operation, if a spark plug 31 in a recreation type of vehicle becomes fouled and requires cleaning, the cover 16 and plug 18 in end A are first removed from aperture 22, with care being taken to hold the container 11 upright to prevent loss of cleaning fluid from within. The pointed end 32 of the file 21 is then used to remove carbon deposits from the electrode area 33 of the spark plug 31 and the cutting surface 34 of the file 21 is used to deglaze the center electrode 35 and the ground electrode 36. The fact that the file 21 is 0.025 inch thick makes it possible to use the same as an accurate guide for setting the electrode clearance 37. The plug 18 with the file 21 is then replaced in the container 11 and the cover 16 tightened to prevent loss of cleaning fluid.

The cover 24 and plug 26 in end B are then removed from aperture 27, with care also being taken to prevent loss of fluid from within the container 11, and the brush 30 is used to wash both the electrodes 35 and 36 and the spark plug threads 38. The spark plug 31 is then threadedly engaged into aperture 27 in end B (unless it has a thread size to require engagement in end A) and the spark plug 31 and container 11 are then shaken vigorously to permit the cleaning fluid to remove any oil and remaining deposits from the electrode area 33.

The spark plug 31 is then removed and the plug 26 and brush 30 are then replaced in end B of the container 11 and the cover 24 tightened to prevent any loss of cleaning fluid. The spark plug 31 is then ready for replacement in the engine.

The axial offset disposition of the file 21 and brush 30 places the cutting surface 34 of the file 21 generally tangential to the periphery of the brush 30 so that the file scrapes the brush as they are replaced in the container 11 (see FIG. 2), and this achieves a mutual self-cleaning of both file and brush. The offset location further permits the file 21 and brush 30 to nest together without interference within container 11.

The device of the instant invention is particularly suited for spark plug cleaning and maintenance in motorcycle, snowmobile, boat, dunecycle, chain saw and like engines. The device, however, may be used for other emergency purposes as, for example, ignition drying; and the cleaning of fuel and air filters; throttle, brake and clutch cables; starting ropes; handle grips; drive belts; clutch and brake linings; and general part

cleaning. And as can be readily seen, the container 11 may be refilled with cleaning fluid as necessary.

I claim:

1. A spark plug cleaning device comprising:
a cylindrical container adapted to contain a cleaning fluid;
end closure means for each end of said container;
a first internally threaded aperture axially disposed in one of said end closure means;
first externally threaded plug means adapted to be removably received in said first internally threaded aperture;
generally axially extending file means mounted in said first externally threaded plug means and adapted to be disposed internally of said container;
a second internally threaded aperture axially disposed in the other of said end closure means;
second externally threaded plug means adapted to be removably received in said second internally threaded aperture;
generally axially extending brush means mounted in said second externally threaded plug means and adapted to be disposed internally of said container;
said file means and said brush means being axially offset with respect to each other to permit the same to nest together and mutually clean each other as they are replaced in said container;
each of said internally threaded apertures in said end closure means being adapted to receive a threaded end portion of a spark plug to be cleaned.
2. A spark plug cleaning device as in claim 1 wherein said brush means is mounted in said second externally threaded plug means coaxially with the axis of said container and said file means is mounted in said first externally threaded plug means offset from said axis of said container, the surface of said file means being generally tangential to the periphery of said brush means.
3. A spark plug cleaning device as in claim 1 wherein the diameter of each of said internally threaded apertures in said end closure means is adapted to receive a spark plug threaded end portion of a different diameter.
4. A spark plug cleaning device as in claim 1 wherein the thickness of said file is equal to a desired spark plug electrode gap.
